(57) CLAIM

The ornamental design for a poker game playing surface and environment, as shown and described.

DESCRIPTION

This application is related to a U.S. Utility application Ser. No. 14/486,390, entitled "Method and System for a Card Game Variant of a Community Style Poker Game", which is incorporated herein by reference in its entirety.

FIG. 1 is a front view of a poker game playing surface and environment illustrating a new design;

FIG. 2 is an enlarged front view of reference number 2 as shown in FIG. 1;

FIG. 3 is a front view of a second embodiment of a poker game playing surface and environment;

FIG. 4 is an enlarged front view of reference number 4 as shown in FIG. 3;

FIG. 5 is a front view of a third embodiment of a poker game playing surface and environment;

FIG. 6 is an enlarged front view of reference number 6 as shown in FIG. 5;

FIG. 7 is a front view of a fourth embodiment of a poker game playing surface and environment;

FIG. 8 is an enlarged front view of reference number 8, as shown in FIGS. 1, 3, and 5;

FIG. 9 is an enlarged front view of another embodiment of reference number 8;

FIG. 10 is an enlarged front view of another embodiment of reference number 4; and,

FIG. 11 is an enlarged front view of another embodiment of reference number 4.

1 Claim, 11 Drawing Sheets
